UNITED STATES PATENT OFFICE.

HOWARD E. COFFIN, OF DETROIT, MICHIGAN.

EXPLOSION-ENGINE.

1,153,676.

Specification of Letters Patent. Patented Sept. 14, 1915.

Application filed April 27, 1911. Serial No. 623,677.

To all whom it may concern:

Be it known that I, HOWARD E. COFFIN, a citizen of the United States of America, residing at Detroit, in the county of Wayne, 5 and State of Michigan, have invented certain new and useful Improvements in Explosion-Engines, of which the following is a specification, reference being had therein to the accompanying drawings.

10 The invention relates to explosion engines of that type in which rotary valves are employed for controlling the ports of the cylinder, and the invention consists in the peculiar construction and arrangement of the 15 valve and its seat and connecting passages as more fully hereinafter set forth.

Figure 1 is a central longitudinal section through the cylinder and through the valve in cross section; Fig. 2 is a bottom sectional 20 plan view on line α — α Fig. 1.

25 A is the cylinder of the engine, B is a detachable head for said cylinder which is chambered to form a cylindrical valve seat C having a transverse axis, a water jacket D almost completely surrounds said seat, and 25 passages E, F, G and H communicating with ports in the valve case.

30 It is the object of the invention to protect the valve from the pressure developed by explosion and also from the high heat of combustion, and at the same time it is an object to provide easy passage for the gases through the valve ports and connecting channels.

35 These objects are attained first by reducing the size or diameter of the cylinder valve to the minimum and by forming a comparatively narrow elongated port therethrough, second, by completely surrounding 40 the valve with the exception of ports with the valve case so as to reduce the surface exposed to the pressure of explosion to the minimum, and third, by enlarging or flaring the passages E, F, G and H from the ports 45 communicating with the valve.

As shown, the passage E extends to one side of the head B and communicates with a port I in the valve case which is diametri-

cally opposite to the port J communicating with the passage F. In the same manner the passage G extends from the opposite side of the head B and connects with the port K in the valve case diametrically opposite the port L therein communicating with the passage H. The walls of both the passages E 55 and G are curved so as to gradually change the direction thereof. The passages H and F communicate with the end of the cylinder and between these passages is a portion M of the valve case which protects the valve 60 from the pressure of explosion and which has a water chamber for absorbing the heat.

N is the rotary valve having the central narrow elongated passage O for successively connecting the ports I, J, K and L. 65

With the construction as described in operation, the valve is constantly rotated by any suitable drive connection (not shown) and when in registration with the ports will alternately open the inlet and exhaust passages. As it is protected both from the pressure and heat the difficulties encountered with many constructions of rotary valves for explosion engines are overcome. 70

What I claim as my invention is:

In an explosion engine, the combination with the cylinder, of a head therefor having a transversely arranged cylindrical valve seat, a rotary valve in said seat having a single passage therethrough, inlet and exhaust passages leading from said seat to the cylinder, said passages being of the same size at the seat as said single passage through the valve, and diametrically opposite continuations of said inlet and exhaust passages 80 leading out through the opposite side walls of the head, all of said passages and continuations enlarging from the ports in the seat to their opposite ends and said continuations having the walls thereof curved. 85

In testimony whereof I affix my signature in presence of two witnesses.

HOWARD E. COFFIN.

Witnesses:

JAMES P. BARRY,
W. K. FORD.
